UNITED STATES PATENT OFFICE.

JOHN E. BUXTON, OF OWATONNA, MINNESOTA.

KNOTTER FOR GRAIN-BINDERS.

SPECIFICATION forming part of Letters Patent No. 267,972, dated November 21, 1882.

Application filed May 26, 1882. (Model.)

To all whom it may concern:

Be it known that I, JOHN E. BUXTON, a citizen of the United States, residing at Owatonna, in the county of Steele and State of Minnesota, have invented certain new and useful Improvements in Knotters for Grain-Binders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 is a side elevation. Fig. 2 is a vertical central section of the knotter proper.

This invention relates to improvements in knotters for grain-binders; and the novelty consists in combining in the bill a cutting-edge and a holding device, all as will now be explained.

In the drawings, A denotes the shank by which the knotter is connected with its actuating mechanism. In the lower jaw, C, of the head B is a stationary blade, E, having a knife or cutting-edge, e, and above it is the hinged cord gripping and holding jaw D, having a heel-extension, d, by means of which, as the shank A is revolved and the said heel-extension is brought in contact with some operating device, the jaw will be opened and closed at the proper times.

In operation, the cord gripping or holding jaw will serve to detain and hold the twine or cord secure while the process of tying the knot is being carried on, and will then release it at the proper moment. The cutting will be done in the edge e. This cutting-edge is at the front part or end of the blade E. Said blade is so applied or fixed in the lower jaw, C, of the head that it can readily be fixed in place or removed. This is now indicated by the screw c, which passes through the lower jaw and the blade.

45 The device as thus constructed is readily adapted to any ordinary grain-binder, but is more especially designed for such a one as is

shown in my patent of October 11, 1881. To the upper part of the shank any suitable attachment may be made for connecting the knotter with the driving parts of the machine. The cord is held in the cord-holder in front of the knotter, and when the binder-arm moves back it carries the cord and places it over the knotting-hook. As soon as the packer has gathered the grain into a gavel, and there is sufficient pressure to trip the binder-arm into gear, the cord is brought around the gavel by the binder-arm and over the knotter and to the cord-holder. Then the two cords, or two parts of the cord, are lying together over the knotter, which now revolves, and having thereby formed the loop at about the completion of one revolution, it receives the said two cords into its open mouth, and the compressing-jaw 65 is now forced down upon the two cords and holds them firmly while the loop is pulled off over the points of the knotter. At about the same time the bundle-discharger, acting on the bundle, pulls the loop off the knotter and over 70 the bow that has been formed, which bow is caught by the hooked end of the knotter and cut by the knife in the end.

Having thus described my invention, what I consider new, and desire to secure by Letters 75 Patent, is—

1. A cord-knotter for grain-binders provided with two rigid jaws, in the end of one of which is fixed a knife or cutting device, and pivoted in the other is a compressing or holding jaw 80 having an outwardly-extending heel or tail piece, whereby it is actuated, all substantially as shown and described.

2. In a cord-knotter for grain-binders, the head B, having two rigid jaws, the blade E, 85 provided with cutting-edge e, and the pivoted holding-jaw D, constructed and operating substantially as described.

In testimony whereof I affix my signature in presence of two witnesses.

JOHN E. BUXTON.
